UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

MACHINE-LEVELING MEANS.

Application filed August 4, 1923. Serial No. 655,645.

Large concrete pavers, of the class shown in my United States Letters Patent No. 1,141,470 of June 1, 1915, embody a mixer for concrete, a boom and bucket mechanism to distribute the concrete in the form of an attachment extending from the rear end of the machine, and usually a loading skip and batch box handling derrick or crane at the front end of the machine. These machines are being used today to much advantage in all road construction including roads in hilly and mountainous country where the grade inclination is very considerable. The foregoing represents one problem encountered in the operation of these machines making necessary adjusting means to maintain the boom and bucket distributor horizontal for its efficient operation.

Another problem of use of concrete pavers of the class referred to is involved in constructing roads banked or upraised at the outside of curved sections, known as super-elevated curves. This method of banking the road pavement is coming into use more and more, and, necessarily the paving machine that handles the concrete must travel on a banked sub-grade which tilts the machine and its supported attachments to one side unless some means is utilized to prevent such action. Here, again, is a condition under which the boom and bucket attachment and batch box crane cannot operate with highest efficiency as the machine is usually constructed, and, furthermore, in certain types of machine other features of the mechanism such as the skip, and batch-box loading crane are similarly affected.

My invention contemplates, therefore, a design of concrete paver with adjusting means by which the base or chassis of the machine may be properly adjusted to enable the boom and bucket distributor to operate in horizontal or substantially horizontal positions at any point in its customary range of swinging movement, and whereby the machine may be generally leveled.

My invention contemplates the provision of a concrete paver with means to adjust the same to accommodate for a proper functioning of the boom and bucket, or crane and skip, or all of such means when the machine is working up or down grade, endwise speaking, and on super-elevated curves which are provided to bank the pavement

properly in either direction side-wise or across the road sub-grade.

My invention makes provision for leveling means by the use of special adjusting devices intermediate the chassis or frame of the machine to which the invention is applied and the supporting wheels or axle. The said adjusting devices are susceptible of independent adjustment to enable one side of the machine to be elevated or lowered relatively to the other, or the adjusting devices may be operated to effect a correspondence of adjustment thereof, relatively speaking, this being desirable when the machine is on a level roadgrade. Again, the adjusting devices are adjustable so that either end of the machine may be elevated or lowered relatively to the other.

Not only is the leveling of the machine for insuring proper operation of the distributing device (either a boom and bucket, or chute attachment) highly desirable, but it is likewise very important to obtain proper action of the crane or derrick means that handles the batch boxes, and is supported on the frame or body of the machine. Moreover, if the machine body is adjusted relative to its traction base there becomes necessary adjustment of the pivot connections between the skip and said body, so the skip will not hit the ground at an angle.

The provisions made, therefore, by the invention are such as will enable the correct operation of the crane or derrick feature aforesaid, and enable the skip to be adjusted so it will drop to the subgrade and rest flatly thereon even though the latter is not level. The latter proposition involves the use of special adjustable connections between the skip and its pivot bracket connections with the frame of the machine.

Upon consideration of the foregoing it will be apparent that the invention provides means to level the whole paving machine, practically speaking, to maintain stability and operativeness of the distributor and the batch box loader, and means to adjust the skip as required by the adjustment of the body of the machine, especially where a side-wise slant or banking of the sub-grade makes necessary the said relative adjustment of the machine body and its traction base.

Figure 1 is a diagrammatic side view of a concrete paver shown as ascending a grade,

as when laying pavement on the sub-grade or hilly or mountainous country;

Figure 2 is diagrammatically illustrative of the way in which my leveling means is mounted between, say, the rear axle construction of the machine and the chassis;

Figure 3 illustrates a front axle construction of a paver where three point suspension is used and which eliminates the necessity for special leveling means between the front end of the machine and frame or chassis;

Figures 4 and 5 are sectional views on the lines 4-4 and 5-5, respectively, of Figure 9 and showing more clearly the parts thereof in illustrated;

Figure 6 is a detail view of the upper adjusting or cam member;

Figure 7 is a detail view of the lower of said adjusting members;

Figure 8 is a front view of the frame of a heavy machine mounted on wheels or endless traction members, and illustrating the preferred embodiment of the invention;

Figure 9 is an enlarged front view of one of the bearing brackets showing more clearly the adjusting members, the axle bearing members, and the connection between the lower adjusting member and the upper of the bearing members; and

Figure 10 is a side view of the parts shown in Figure 9.

Figure 11 is an enlarged side view of the skip, broken away, and the adjustable means connecting it to its pivot bracket.

Figures 12 and 13 are top and end views of the same.

Figure 14 is a front end view of the paver showing one of the sidewise adjustments of the skip for its regular longitudinal tilting operation to elevate and discharge a load of aggregates into the mixer.

Referring in a general way to Figures 1 to 3 inclusive, I might note that the features of construction diagrammatically shown involve a paver which comprises the base frame or chassis A on which is mounted the mixer B, the chassis being carried by multi-planes or endless traction devices C, in lieu of which, however, wheels might be employed as found desirable. On the front end of the machine is mounted the loading skip D and at this same end, but at one side of the machine, is carried the batch box loading derrick or crane E having the boom F shown as supporting a batch box G. From the rear end of the machine the boom H of a boom and bucket distributing attachment projects in the usual way and carries the bucket I which is moved back and forth by suitable means, this boom and bucket attachment being largely as set forth in my Letters Patent previously identified herein.

Machines of the type improved upon by my invention may have the frame or chassis A supported on front and rear axles by

rigid means somewhat as shown diagrammatically in Figure 2 and also in Figure 8 where one type of my adjusting mechanism is illustrated. On the other hand, in certain constructions of pavers now in use, notably the Koehring type, there is a rigid mounting of the rear end of the machine at which the boom and bucket distributor is located, and a pivoted mounting of the front end where the skip and the batch box frame are located. The pivoted mounting mentioned is characterized in the art as a three point suspension, involving a pivoting of the frame or chassis A to the middle of the front axle as shown at G. The axle itself is designated B' and will not be described in detail as to its mounting because this will be obvious to any one versed in the art.

Where a paver is constructed with rigid connections between the axles and both ends of the frame or chassis A, my adjusting or leveling devices to be hereinafter set forth in detail may be employed at both ends of the frame or machine body intermediate its respective sides and the opposite ends of the respective axles. Where, however, I use a three point suspension for the front end of the machine I contemplate that the leveling means which adjusts the rear end will of course adjust the body of the machine upon the front axle by a lateral pivotal movement, so far as adjustments may be required for leveling the machine parts in laying the pavement on super-elevated curves, so-called. Where the leveling means in this particular construction is possessed of a fairly wide range of adjustment, it may be suitably used to move the rear end of the machine up or down relatively to the front end in obtaining a leveling action for the purpose heretofore referred to, in conjunction with operations on grades where one end of the machine has to be either higher or lower than the other. The controlling factor is whether the grade is ascending or descending, of course.

It is therefore to be understood that my invention contemplates a use of leveling means such as I shall particularly point out and describe in one construction, herein-after, utilized between the ends of both front and rear axles where necessary, between both ends of a rear axle where the front axle is mounted on the three point suspension principle, or between both ends of a rear axle only, irrespective of the mounting of the front axle, when the adjusting means will afford a suitable adjustment up and down for the rear end of the machine in relation to the front end.

Secured in any substantial manner to said frame A for cooperation with an axle B'' are the supporting brackets 1 which might be characterized as of somewhat skeleton construction in that they are slotted to some extent both between the sides and between

the front and rear portions. Mounted in slots or open spaces between the sides of each bracket 1 are the adjusting instrumentalities comprising the upper adjusting member, 5 cam or wedge 2 and the lower adjusting member, cam or wedge 3. The said members 2 and 3 have the adjacent surfaces thereof contacting and disposed at a wedging inclination so that by moving these 10 members longitudinally relative to one another the upper surface of the upper member 2 and the lower surface of the lower member 3 will be separated or brought closer together, with a resulting camming or wedging 15 action which is produced upon the parts engaging said particular surfaces, all in an obvious manner in view of the common knowledge of the action of wedging.

To prevent displacement of the adjusting 20 members 2 and 3 from their particular bracket 1, I form outwardly projecting ribs 2^a at the top of the member 2 engaging above ribs 4 at the opposite sides of the slot or clearance space of the bracket 1 in which 25 the members 2 and 3 are mounted. Projecting inwardly from the opposite sides of said clearance space of the bracket 1 are the inclined ribs 5 and the lower adjusting member 3 is provided with spaced ribs 6 which 30 in effect produce grooves 7 at opposite sides of said member, said grooves adapted to receive the ribs 5. The arrangement of the ribs 4 and 5, together with the pulling and pushing devices that cooperate with the 35 members 2 and 3 to produce their camming or wedging action, obviates liability of unauthorized displacement of the parts 2 and 3 from the bracket 1.

The upper adjusting member 2 engages a 40 bearing surface 8 of the bracket 1, the same being a horizontal web, practically speaking, and the lower side of the member 3 is formed with a curved bearing element 3^a which is seated in an arcuate-shaped seat 45 or recess 9 in the upper bearing member 10 mounted in the bracket 1 to engage the upper side of the axle B''. The upper bearing member 10 is secured to a lower bearing member 11 by suitable bolts 12 or the like, 50 and the axle B'' is received between said bearing members and preferably is a non-turning axle, though this is immaterial within the purview of the invention.

At the outer ends thereof the axle B'' has 55 secured thereto wheels or endless tread devices which will be termed traction members 13 for the purposes of this description. Sprockets or other driving means 14 may be connected with said traction members 13. 60 The bearing members 10 and 11 are freely movable up and down in the bracket 1 through the provision of a suitable clearance space in the bracket, in which space said members may operate.

65 I now come to the means used by me for

moving the members 2 and 3 relatively to one another. Said means is virtually a pulling and pushing device intended to pull the adjusting members 2 and 3 together, or in one direction, or in opposite directions, so 70 to speak, to increase the distance between the upper surface of the member 2 and the lower surface of the member 3 and thereby move the engaged bearing member 10 and axle B'' downwards. An opposite movement of the pulling and pushing member will produce an opposite result, in an obvious manner. 75

The pulling and pushing members are provided one for each bracket 1, or one for each 80 set of the adjusting members 2 and 3. They are best shown in Figures 3, 4 and 5, and each comprises a screw 15 having a turning handle or crank 16 at one end and near that end passing through an opening in the larger 85 end of the adjusting member 3. A swivel connection between said screw and said portion of the adjusting member 3 is produced by bosses 17 on the screw at opposite sides of the wall of the member 3 through which the screw passes. Said member 3 is slotted 90 so that at its other end the screw 15 may operate in a sort of clearance space, and likewise the member 2 is similarly slotted for the same purpose. 95

As seen best in Figures 5 and 6, the screw portion of the screw 15 passes through the right hand end wall of the adjusting member, cam or wedge 2 at the point 2^b and also passes through the outer end of a loop 2^c formed with said wall of the member 2. The loop 2^c being spaced at its outer end from the adjacent end of the wall 2 provides a small space for a nut 18 screwed on the screw 15 and providing an abutment between the screw and the part 2. 105

With the foregoing explanation of construction, it will be evident that by the simple turning of the screw 15 by the crank 16 the adjusting members, cams or wedges 2 110 and 3 may be pushed or pulled in opposite directions to thereby adjust the end of the axle B'' with which a particular set of said members coacts. This adjustment, of course, may be by an up or down movement of the 115 bearing members 10 and 11, and I utilize the curved contacting parts 3^a and 9 between the members 3 and 10 in order to accommodate for a tilting of the axle B transversely to the member 3, necessarily resulting in a sort of arcuate movement of the axle, relatively speaking, with the center of movement slightly below the curved bearing element 3^a of the lower adjusting member 3. Figure 8 120 illustrates how one end of the axle is adjusted above the other end to accommodate for a leveling of the machine frame A, as when the surface on which the machine is traveling or stationary, is lower at one side 125 than the other. 130

Of course the adjustment of the body A of the machine relative to the traction base C takes care of the required adjustment of the crane attachment E, as well as the distributor H—I, which latter might be of the spout or chute type so far as this feature of the machine, and its advantages, are concerned. It is within the purview of my invention, however, to use special adjusting means for the crane feature; and for the distributor, irrespective of use of those means set forth herein to adjust the body A relatively to the base C. The adjustment of the crane feature to level it is highly important, furthermore, because the crane is operated every time a batch of aggregates is to be introduced into the mixer (usually once a minute), whereas the swinging of the distributor horizontally is performed less frequently.

Referring now to the skip construction of Figs. 11 to 13 inclusive, it will be seen that the skip D is carried by the bracket 20 directly pivoted to the framework of the machine. Obviously an adjustment of the body A to accommodate for banked grades, as for instance illustrated on Figs. 2, 3 and 14, or reverse inclinations of the subgrade, correspondingly adjusts the frame of the machine on said body. This would cause the skip to remain with its bottom level or horizontal (laterally of the subgrade) when the subgrade inclines for banking purposes, if not provided against. I avoid difficulty in this connection by means now to be set forth.

On the upper end of the skip is a sort of socket plate 21, equipped with offstanding side lugs 21^a slotted downwardly at 22. At outermost portions the plate 21 has apertured lugs 23, the apertures of which coincide with those of lugs 24 on the outermost parts of a casting 25 riveted to the sides of the bracket structure 20. Adjusting bolts 26 pass through the lugs 23 and 24 at opposite sides of the skip and its bracket casting, and by turning the nuts 27 properly, the skip D will be given a rotative movement within the space between the bracket sides and thus adjusted angularly until its bottom is parallel with the lateral slant of the subgrade and thereby enabled to rest flat thereon, (see Fig. 14). The adjustment of the skip D relatively to its bracket structure is preferably fixed by the locking bolts 28 that enter the slots 22 of the lugs 21 and pass through the sides of the bracket structure 20. In lieu of the means just described the skip D may be left undisturbed at its pivotal mounting and a chock of tapering form adjustably applied to its bottom to thus properly support the skip when it is down on the subgrade.

It is almost obvious, additionally, that if the machine is to be positioned for work on a road or surface such that ordinarily

the front end of the machine or the rear end would be at a different level from its opposite end, a leveling of the frame A may be produced merely by adjusting the screws 15 so that the adjusting members 2 and 3 of both sets for one axle B'' will be at substantially the same relative positions and properly adjusted as regards the sets of said members at the opposite end of the machine, to cause an elevation or lowering of the particular end of the machine requiring adjustment, as the case may be.

While I have illustrated a preferred embodiment of the invention as including special adjusting devices of a particular form, I do not wish to be limited thereto necessarily, for my invention comprehends the employment of other divers expedients in the nature of similar mechanical structures by which like results may be produced.

Having thus described my invention, what I claim as new and desire to secure by Letters Patent is:

1. In a machine of the class described, in combination, a portable supporting frame, means to be supplied with materials mounted upon said frame, a loading device for supplying said materials to said previously mentioned means and adapted to rest upon the ground; and an adjustable connection between the supporting frame and said loading device whereby the latter may rest in proper contact with the ground even though the portable supporting frame is inclined to the horizontal.

2. In a machine of the class described, in combination, a portable supporting frame, a body structure mounted upon said frame, means intermediate the two whereby they may be relatively adjusted so that the body structure will remain horizontal even if the supporting frame is disposed at an angle to the horizontal, a loading device connected with said body structure, adapted to rest upon the ground and movable into an elevated position to discharge its contents, and an adjustable connection between said loading device and said body structure whereby the loading device may be turned relatively to the body structure to enable the loading device to rest upon the ground in proper supported relation relative thereto.

3. In a machine of the class described, in combination, a portable supporting frame, a body structure mounted upon said frame, means intermediate the two whereby they may be relatively adjusted so that the body structure will remain horizontal even if the supporting frame is disposed at an angle to the horizontal, a loading device connected with said body structure, adapted to rest upon the ground and movable into an elevated position to discharge its contents, and an adjustable connection between said loading device and said body structure whereby

the loading device may be turned relatively to the body structure to enable the loading device to rest upon the ground in proper supported relation relative thereto, the said 5 loading device comprising a load skip having a relatively large wide receiving end, the bottom of which is adapted to rest upon the ground.

4. In a machine of the class described, in 10 combination, a portable supporting frame, a body structure mounted upon said frame, means intermediate the two whereby they may be relatively adjusted so that the body structure will remain horizontal even if the 15 supporting frame is disposed at an angle to the horizontal, a loading device connected with said body structure, adapted to rest upon the ground and movable into an elevated position to discharge its contents, and 20 an adjustable connection between said loading device and said body structure whereby the loading device may be turned relatively to the body structure to enable the loading device to rest upon the ground in proper 25 supported relation relative thereto, said adjustable connecting means for the loading device comprising a bracket permanently pivoted to the body structure and a rotative connection between said bracket and the 30 loading device for the purpose set forth.

5. In a machine of the class described, in combination, a portable supporting frame, a body structure mounted upon said frame, means intermediate the two whereby they 35 may be relatively adjusted so that the body structure will remain horizontal even if the supporting frame is disposed at an angle to the horizontal, a loading device connected with said body structure adapted to rest upon the ground and movable into an elevated position to discharge its contents, and an adjustable connection between said loading device and said body structure whereby the loading device may be turned relatively 40 to the body structure to enable the loading device to rest upon the ground in proper supported relation relative thereto, said adjustable connecting means for the loading device comprising a bracket permanently 45 and pivotally attached to the body structure, adjustable connecting means between the loading device and the bracket including parts operable for effecting relatively turning of the loading device on the bracket, and other parts for holding the loading device at a certain adjustment relatively to the bracket after said turning movement. 50

6. In a machine of the class described, in 55 combination, a portable supporting frame, a body structure mounted upon said frame, means intermediate the two whereby they may be relatively adjusted so that the body structure will remain horizontal even if the supporting frame is disposed at an angle to the horizontal, a loading device connected

with said body structure, adapted to rest upon the ground and movable into an elevated position to discharge its contents, and an adjustable connection between said loading device and said body structure whereby 70 the loading device may be turned relatively to the body structure to enable the loading device to set itself upon the ground in proper supported relation relative thereto, the 75 said loading device comprising a load skip having a relatively large wide receiving end, the bottom of which is adapted to rest upon the ground, the loading skip comprising bracket connecting means between it and the body structure including a bracket 80 permanently mounted on the body structure, a socket plate adjustably connected with said bracket and attached to the skip, fastening means whereby the socket plate may be moved bodily relatively to the bracket to cause it to assume a certain adjustment upon the bracket and other fastening means for setting the socket plate and bracket against unauthorized relative movement, after adjustment thereof has been 85 secured. 90

7. In a concrete paving machine comprising a portable supporting frame, a concrete mixer mounted thereon, and a boom and bucket mounted to travel longitudinally thereon carried by said supporting frame and adapted to swing horizontally, and adjusting means for raising or lowering one end of the supporting frame in relation to the other to maintain the said supporting frame and boom substantially horizontal when the machine is operating upon ascending or descending grades. 95

8. In a concrete paving machine comprising a portable supporting frame, a concrete mixer mounted thereon, and a boom and bucket mounted to travel longitudinally thereon carried by said supporting frame and adapted to swing horizontally, and adjusting means for raising or lowering either side of the machine relatively to the other to maintain the supporting frame and boom substantially horizontal with its supported boom and bucket mechanism when the machine is working on a subgrade one 105 side of which is higher than the other. 110

9. In a concrete paving machine comprising a portable supporting frame, a concrete mixer mounted thereon, and a boom and bucket mounted to travel longitudinally thereon carried by said supporting frame and adapted to swing horizontally, and adjusting means for the supporting frame for raising and lowering an end of the same relatively to its opposite end to accommodate for operation of the machine on ascending and descending grades longitudinally thereof, and for adjusting a side of the supporting frame relatively to its other side to 120 accommodate for operation of the machine 125 130

on road sub-grades where one side is higher than the other, substantially as set forth.

10. In a concrete paving machine comprising a portable supporting frame, a concrete mixer mounted thereon, and a boom and bucket attachment carried by said supporting frame and adapted to swing horizontally, adjusting means for the supporting frame for raising and lowering an end 10 of the same relatively to its opposite end to accommodate for operation of the machine on ascending and descending grades longitudinally thereof, and for adjusting a side 15 of the supporting frame relatively to its other side to accommodate for operation of the machine on road sub-grades where one side is higher than the other, and a loading skip and a batch box loading crane carried by the supporting frame of the machine opposite the boom and bucket mechanism, the portable feature of the supporting frame comprising traction members with front and rear axles connecting them with the supporting frame, the front axle being mounted 20 upon the frame on the three point suspension principle and the adjusting means aforesaid connecting the rear end of the frame with the rear axle, all for the purpose 25 set forth.

30. 11. In a concrete paving machine, a portable support, a superposed body thereon, a concrete mixer carried by the body, a crane attachment comprising a swinging boom mounted on said body, and means cooperat-35 ing with the support and body to raise or lower either end of the body relative to the other, and relatively to the portable support, to maintain the body and crane sub-stantially level when the machine is operat-40 ing on ascending and descending subgrades.

45. 12. In a concrete paving machine, a portable support, a superposed body thereon, a concrete mixer carried by the body, a crane attachment comprising a swinging boom mounted on said body, and cooperating sliding means coacting with the support and body to raise or lower either side of the body relative to the other, and relatively to the portable support, to maintain the 50 body and crane substantially level when the machine is operating on laterally banked subgrades.

55. 13. In a concrete paving machine, a portable support, a superposed body thereon, a concrete mixer carried by the body, a crane attachment comprising a swinging boom mounted on said body, and means to raise or lower either end or either side of the body relative to the other, and relatively to the 60 portable support, to maintain the body and crane substantially level when the machine is operating on ascending and descending subgrades or on laterally banked subgrades, respectively.

65. 14. In a concrete paving machine compris-

70. ing a portable supporting frame, a concrete mixer mounted thereon, and a boom and bucket attachment carried by said supporting frame and adapted to swing horizontally, adjusting means for the supporting frame for raising and lowering an end of the same relatively to its opposite end to accommodate for operation of the machine on ascending and descending grades longitudinally thereof, and for adjusting a side 75 of the supporting frame relatively to its other side to accommodate for operation of the machine on road sub-grade where one side is higher than the other, and a loading skip and a batch box loading crane carried by the supporting frame of the machine opposite the boom and bucket mechanism, the portable feature of the supporting frame comprising traction members with front and rear axles connecting them with the supporting frame, the front axle being mounted upon the frame on the three point suspension principle and the adjusting means aforesaid connecting the rear end of the frame with the rear axle, all for the purpose set forth, 80 and means adjustably connecting the loading skip to the supporting frame so that the bottom of the skip may rest flat on the subgrade when the latter is at an angle to a horizontal plane including the base of the 85 frame.

90. 15. In a concrete paving machine, a portable support, a superposed body thereon, a concrete mixer carried by the body, a crane attachment comprising a swinging boom 95 mounted on said body, and means to raise or lower either end of the body relative to the other, and relatively to the portable support, to maintain the body and crane sub-stantially level when the machine is operat-100 ing on ascending and descending subgrades, a loading device connected to the body, and means for adjusting the loading device relatively to the body so the loading device may rest flat on a subgrade located at an 105 angle to a horizontal plane including the body.

110. 16. In a concrete machine, a portable support, a superposed body thereon, a concrete mixer carried by the body a crane attach-115 ment comprising a swinging boom mounted on said body, and means to raise or lower either end of the body relative to the other, and relatively to the portable support, to maintain the body and crane substantially 120 level when the machine is operating on ascending and descending subgrades, a loading device connected to the body, and means for adjusting the loading device relatively to the body so that loading device may rest flat on a subgrade located at an angle to a horizontal plane including the body, and a concrete distributor carried by the body and maintained level by movement of the body 125 relatively to its portable support.

17. In a concrete paving machine, a portable support, a superposed body thereon, a concrete mixer carried by the body, a crane attachment comprising a swinging boom mounted on said body, and means to raise or lower either end of the body relative to the other, and relatively to the portable support, to maintain the body and crane substantially level when the machine is operating on ascending and descending subgrades, and a concrete distributer carried by the body and maintained operatively level by adjustment of the body relatively to its support.
18. In a concrete paving machine, a portable support, a superposed body thereon, a concrete mixer carried by the body, a crane attachment comprising a swinging boom mounted on said body, and means to raise or lower either side of the body relative to the other, and relatively to the portable support, to maintain the body and crane substantially level when the machine is operating on laterally banked subgrades, and a concrete distributer projecting from the body and maintained operatively level by an end adjustment of the body relatively to its support.
19. In a paving machine, a traction support, a body structure thereon, boom and bucket traveling thereon paving apparatus mounted upon the body structure, and means for adjusting said boom and bucket apparatus relatively to the traction base whereby to maintain this apparatus operative in a substantially horizontal plane of movement irrespective of conditions of relative inclination of the body structure and traction base.

In testimony whereof I affix my signature.

ERICH H. LICHTENBERG.
